UNITED STATES PATENT OFFICE.

ISAAC A. SHEPPARD, OF PHILADELPHIA, PENNSYLVANIA.

DESIGN FOR RANGE.

SPECIFICATION forming part of Design No. 11,815, dated June 8, 1880.

Application filed April 20, 1880. Term of patent 7 years.

To all whom it may concern:

Be it known that I, ISAAC A. SHEPPARD, a citizen of the United States, residing in Philadelphia, Pennsylvania, have invented or produced a new and original Design for a Range, of which the following is a specification.

My design for a range is fully shown in the accompanying photographic illustration, showing a general view of the range and a view of the plates on a larger scale.

The design comprises the oven-door A, fire-door B, and ash-door D.

The oven-door A has a flat rim with ornamental beading *a*, a central raised or convex portion, *b*, ornamented with line-work, and a central rectangular medallion, *d*, with beveled edges, line-work border, and the name "Magic" in relief.

The fire-door B has a beaded border, *e*, two openings, *f*, with beveled corners, and oblong ornaments *g*, of the same character as the border *e*.

The ash-door D has a beaded border, *i*, and a central circular damper with three wings, each of which has an anchor-shaped ornament,

m. The door has triangular corner ornaments *n*, composed of line-work.

I claim—

1. The design for the door A, said design comprising the beading *a*, convex portion *b*, with its line-work ornamentation, and central medallion, *d*, with beveled edges, line-work border, and name in relief, all substantially as shown and described. 30

2. The design for the door B, said design 35 comprising the beaded border *e*, openings *f*, with beveled corners, and oblong ornaments *g*, as shown and described.

3. The design for the door D, said design comprising the border *i*, circular damper with 40 wings having anchor-like ornaments *m*, and the triangular corner ornaments *n*, as shown and described.

In testimony whereof I have signed my name to this specification in the presence of 45 two subscribing witnesses.

ISAAC A. SHEPPARD.
